UNITED STATES PATENT OFFICE.

HARRY DOLSON AND BENJAMIN G. APPLEBY, OF SAGINAW, MICHIGAN.

DESIGN FOR A BICYCLE-STAND.

SPECIFICATION forming part of Design No. 28,458, dated April 5, 1898.

Application filed January 22, 1898. Serial No. 667,655. Term of patent 7 years.

To all whom it may concern:

Be it known that we, HARRY DOLSON and BENJAMIN G. APPLEBY, citizens of the United States, residing at Saginaw, in the county of Saginaw and State of Michigan, have invented and produced a certain new and original Design for Bicycle-Stands; and we do declare the following to be a full, clear, and exact description of the invention, such as will enable others skilled in the art to which it appertains to make and use the same, reference being had to the accompanying drawings, and to the letters of reference marked thereon, which form a part of this specification.

In the drawings, Figure 1 is a perspective of the bicycle-stand. Fig. 2 is a side view of the stand.

As shown in the drawings, the leading or essential feature consists of a board cut in

the shape of a druggist's mortar and supported 20 between two standards B, extending upward from the base A. The lower edge of the board or mortar has notches C cut therein, into any one of which the wheel of a bicycle may pass and be held from falling thereby.

Having thus described our invention, what we claim as new, and desire to secure by Letters Patent, is—

The design for a bicycle-stand as herein shown and described.

Signed by us at the city and county of Saginaw this 19th day of January, 1898.

HARRY DOLSON.
BENJAMIN G. APPLEBY.
